Specification for Design.

Patented Sept. 26, 1916.

Application filed August 11, 1915. Serial No. 45,058. Term of patent 14 years.

To all whom it may concern:

Be it known that I, CHAUNCEY W. ABBOTT, a citizen of the United States, residing at Pittsburgh, in the county of Allegheny and State of Pennsylvania, have invented a new, original, and ornamental Design for Left-Hand-Twisted Elbow-Covers for Fittings for Electrical Conduits, of which the following is a specification, reference being had to the accompanying drawings, forming part thereof.

In the drawings, Figure 1 is an elevation illustrating a side view of a ceiling leg and a front view of a side wall leg, Fig. 2 is an elevation illustrating an end view of the

ceiling leg and a side view of the side wall leg, and Fig. 3 is a plan view illustrating a top view of the ceiling leg and an inside end view of a side wall leg of a left hand twisted elbow cover for fittings for electrical conduits, showing my new design.

I claim:

The ornamental design for a left hand twisted elbow cover for fittings for electrical conduits, as shown.

CHAUNCEY W. ABBOTT.
